Patented June 15, 1971

220,910

PORTABLE CHARGER FOR HEARING AID BATTERIES

Lee Poirier, 619 N. Orchard, Boise, Idaho 83704

Filed Aug. 11, 1969, Ser. No. 18,639

Term of patent 14 years

Int. Cl. D13—02

U.S. Cl. D26—15

Fig. 1.

Fig. 2.

Fig. 3.

Fig. 4.

Fig. 5.

FIG. 1 is an isometric view of a portable charger for hearing aid batteries, showing the new design;

FIG. 2 is a side elevation thereof;

FIG. 3 is an end elevation as seen from the right of FIG. 2;

FIG. 4 is a top plan view thereof; and

FIG. 5 is an elevation as seen from the side opposite FIG. 1.

I claim:

The ornamental design for a portable charger for hearing aid batteries, as shown.
